(57) **CLAIM**

The ornamental design for a work vehicle and body assembly thereof, as shown and described.

DESCRIPTION

FIG. 1 is a perspective view of an embodiment of a work vehicle and body assembly thereof according to my new design;

FIG. 2 is a first side elevational view thereof;

FIG. 3 is a second side elevational view thereof;

FIG. 4 is a first end elevational view thereof, shown enlarged for clarity;

FIG. 5 is a second end elevational view thereof shown enlarged for clarity;

FIG. 6 is a first plan view thereof; and,

FIG. 7 is a second plan view thereof.

The broken line representations in the figures depict unclaimed environment and form no part of the claimed design.

1 Claim, 7 Drawing Sheets
